SPRAY GUN

Fritz Wahlin, Chicago, Ill., assignor to Binks Manufacturing Company, Chicago, Ill., a corporation of Delaware

Application September 4, 1934, Serial No. 742,543

14 Claims. (Cl. 299—140.1)

My invention relates to the class of spray appliances by which the pneumatically propelled and atomized material may be projected either in a spray of conical section, or in a spray of 5 elliptical section flattened to any desired degree and along any desired axis diametric of the spray.

In spray appliances of this class, particularly when constructed as so called spray guns, the flattening of the spray is usually effected by two 10 jets of air issuing from forwardly converging side ports at opposite sides of the axis of the issuing stream of material, while the air for both of these ports is supplied conjointly through a passage which cannot have its inlet on the said axis because 15 the material nozzle must be on that axis. Owing to the just recited requirement the arrangement usually is such that the resulting flattened spray will only be symmetrical in cross-section (with respect to a plane diametric of the 20 axis of the spray) if the air for these side ports is equally divided between the two side ports.

In one of its major objects, my invention aims to provide a simple and inexpensive head construction for a spray appliance of this class 25 which will equalize the supply of air to the two side air ports regardless of the rotational position of the part of the appliance which is provided with these ports.

In a second major object, my invention aims 30 to provide an unusual light inexpensive and conveniently arranged valve arrangement for controlling the total air supply to the said side air ports.

More particularly, my invention aims to provide 35 a control valve arrangement for the recited purpose in which the movable valve member together with the means for actuating this member are supported by the body of the spray gun, while the port controlled by the said member is in a part of the detachable head of the gun, thereby permitting a variety of head constructions to be used interchangeably.

Furthermore, my invention aims to provide a 40 material discharging nozzle for so called liquid nozzle which also has passageways for the air to the side ports and in which these passageways are arranged for equalizing the air supply to the two air ports.

Illustrative of the manner in which I accomplish 45 the above recited objects as well as other advantageous objects,

Fig. 1 is an enlarged side elevation of forward 50 portions of a spray gun embodying my invention, showing this with the air nozzle positioned for flattening the spray along a horizontal plane.

Fig. 2 is a vertical section through the same spray gun parts, taken along the common axis of the material nozzle and of the two side air ports.

Fig. 3 is a horizontal section through the same spray gun parts, taken at right angles to the section of Fig. 2.

Fig. 4 is a perspective view of the liquid nozzle alone.

Fig. 5 is a section taken through the liquid nozzle at right angles to the axis of that nozzle 10 and along the line 5—5 of Fig. 4, with a part of the two-ported baffle flange of this nozzle broken away.

Fig. 6 is a section taken through the air nozzle alone, along the line 6—6 of Fig. 2.

In Figs. 2 and 3, the illustrated forward portion of the spray gun body 1 has a longitudinal bore 2 for slidably guiding the usual needle valve 3 which controls the discharge of the paint or other liquid, and has in its forward end an annular groove 4 concentric with the said bore 2. The gun body also has an air supply passage 5 leading to the groove 4, and a liquid supply passage 6 which has its outlet end coaxial with the said bore 2.

Abutting rearwardly against the forward end of the gun body is a liquid nozzle 7 (shown separately in Figs. 4 and 5) having an axial bore 7a to which the liquid passage 6 in the gun body leads, which passage has its forward portion reduced in diameter and controlled by the needle valve 3. This liquid nozzle is centered, coaxially with the bore 2 which guides the needle valve, by an annular forwardly projecting boss 7a on the gun body which fits into a recess 7b in the said nozzle, and the liquid nozzle is latched against rotating out of the position shown in Fig. 3 by a dowel pin 8 which projects forwardly from the gun body and extends slidably into a bore in the rear end of the said nozzle.

The periphery of the liquid nozzle is formed, as in Fig. 4, so that the rear end of the nozzle presents a peripheral flange 7c adapted to be overhung by the diametrically contracted forward end portion of a clamping ring 9 which has its rear portion threaded on the forward end of the gun body. The liquid nozzle also is formed so as to present three peripheral flanges 10, 11 and 12, spaced longitudinally of the nozzle and having their peripheries in a common conical surface. Moreover, the rear end of the nozzle desirably has an annular groove G coaxial with the nozzle and facing the frontal groove 4 in the gun body, so that these two grooves conjointly constitute an annular air chamber to which air

is supplied through the air passage 5 in the gun body.

The rear end groove G in the liquid nozzle is connected to the peripheral groove g between the flanges 10 and 11 by a port P which extends through the flange 10 and this port is controlled by the hereafter described valve, so that (when this port is open) air flowing from the gun body passage 5 through the cooperating grooves 4 and 10 G will pass through the said port into the groove behind the flange 11. Extending through the last named flange 11 are two ports 14 which have their axes in a common plane p (Fig. 5) diametric of the nozzle and at right angles to the 15 diametric plane p¹ in which the axis of the port P is disposed.

Fitted upon the liquid nozzle is a generally cap-like air nozzle A which has a frusto-conical bore fitting the common taper of the peripheries of the flanges 10, 11, and 12 of the liquid nozzle, as shown in Figs. 3 and 4. This air nozzle has the usual central air port C into which the tip or outlet end of the liquid nozzle freely extends, and also has the usual diametrically opposite 20 horns H through which supplemental air passages 15 lead to forwardly converging side ports S and both of these passages 15 have their inlet ends opposite a peripheral groove g² on the liquid nozzle between the flanges 11 and 12 of the latter nozzle.

Moreover, the liquid nozzle is so formed as to afford an annular space 17 forwardly of the flange 12 and behind the frontal portion A¹ of the air nozzle, and the liquid nozzle has a plurality of 25 longitudinal air passages 18 extending through this nozzle from its rear end groove G, through which air also will flow to the said space and thereafter issue alongside the tip of the liquid nozzle through the central air port C of the liquid 30 nozzle.

When in use, the air nozzle is clamped upon the liquid nozzle by any suitable means, as for example by a retaining ring R which is latched to the air nozzle by a spring ring r and which retaining ring is threaded upon the forward part 45 of the clamping ring 9, as shown in Fig. 3. With the port P in the liquid nozzle open and compressed air supplied to the gun body passage 5, the grooves 4 and G cooperate to afford a large- 50 sectioned annular air passage through which the air will reach both the rearward port P in the liquid nozzle and the longitudinal air passages 18.

The air admitted through the said port P to 55 the groove g in the liquid nozzle then divides and flows in opposite directions (longitudinally of the said groove) to the two ports 14 in the flange 11; and, since the ports 14 have their axes equally spaced from the axis of the port P (as shown 60 in Fig. 5), each of the ports 14 receives an equal amount of air. Consequently, air is supplied at equal pressure to two diametrically opposite portions of the more forward groove g² in the liquid nozzle, which groove has diametrically opposite 65 portions respectively adjacent to the inlet ends of the two horn passages 15 through which air is supplied for the usual side (or spray-flattening) jets. Stated in other words, the middle peripheral flange 11 is a baffle which compels the 70 air in the rear groove g to divide itself between the two ports 14.

With my combination liquid discharging and air distributing nozzle thus constructed, the equalizing of the air supply for the side air jets is obtained regardless of the rotational position

of the air nozzle, which position can readily be changed (when the retaining ring R is slightly loosened) so as to have the spray flattened along any desired plane diametric of the nozzle assembly. For example, if the horn passages 15 have their axes in the same plane (diametric of the nozzle assembly) with the flange ports 14, as shown in full lines in Fig. 6, the air supply from these ports (which was equalized by the previously described location of the said ports with respect to the controlled air port P in the more rearward flange 10 of the liquid nozzle) will obviously be equal.

Likewise, if the air nozzle is rotated to dispose the two opposite as shown in dotted lines at 15' 15 in Fig. 6, each of these ports will still be at the same distance from the outlet of one of the ports 14, so that the air supply for the side air jets will still be equalized. To effect this equalization for all rotational positions of the air nozzle without a material reduction in the air pressure, I desirably also provide the air nozzle with an interior groove 20 from which both horn passages 15 open, this groove 20 being opposite to and facing the groove g² on the liquid nozzle so that the two 25 grooves cooperate to afford an annular air-distributing passage of considerable cross-sectional area.

To control the air-port P conveniently, I desirably provide a valve arrangement supported entirely of the gun body and preferably arranged so that it can readily be manipulated by a finger of the same hand which supports the spray gun. Thus, the drawing shows the gun body as having a bore 21 extending rearwardly into it and opening into the frontal groove 4 in the gun body. To allow for this without materially increasing the weight of the gun, I desirably provide the forward portion of the left side of the gun body with two lateral enlargements 1b and 1c spaced one behind the other to leave room for a valve-actuating wheel W, and contract the diameter of the rearward portion 21a of the bore 21 which is formed in the forward enlargement 1b.

Then I provide a movable valve member which 45 includes a valve stem S having at its forward end a forwardly tapering head H adapted to close the rear or inlet end of the controlled port P, which rear end preferably is at right angles to the axis of the body bore 12. This valve stem 50 extends slidably through the smaller-diaetered bore portion 21a and has a peripheral flange S¹ spaced sufficiently forward from the rear end of the main bore portion 4 to leave room both for an annular packing 23 bearing against that bore 55 end, a metal washer 24 bearing rearwardly against the said packing, and a compression spring 25 interposed between the said washer and the flange S¹ on the valve stem.

Then I thread the portion S² of the valve stem 60 which extends across the space between the body enlargements 1b and 1c of the gun body, and I desirably also provide the rearward enlargement 1c with a guide bore 26 into which the rear end of the valve stem extends. To move the just described valve member longitudinally I provide an exteriorly knurled wheel W having a threaded bore fitting the thread part S² of the valve stem, this wheel being of such a diameter as to project beyond the said body enlargements and of a width 65 slightly less than the spacing between these enlargements.

Thus, arranged, the spring 21 continually urges the valve stem forwardly so as to press the forward end of the wheel W against the rear end of 75

the forward body enlargement 1b, and digital rotations of the said wheel will readily move the valve member longitudinally either forwardly or rearwardly, as the gripping of a part of the stem 5 of the valve member by the packing 23 acts frictionally to prevent the stem from rotating. Moreover, when the retaining ring 9 and the clamping ring R are both unscrewed, the air nozzle and the liquid nozzle can instantly be detached 10 from the gun body. If the wheel W is then rotated to push the valve stem forward to run the wheel off the threaded part of this stem, the valve member can then be grasped by its head H to remove it entirely if desired. Moreover, the bore 15 4 in the gun body also can be flushed out without detaching the valve member, so that all of the novel parts of my spray appliance construction can be easily and speedily cleaned.

Since the combination nozzle shown separately 20 in Fig. 4 serves the combined purposes of a liquid nozzle (or so called material nozzle) and of air equalizing and air-distributing means, no separate baffle member is required, so that I simplify and expedite the cleaning of the appliance after 25 it has been in use. Moreover, my simple and easily manufactured control valve is both light, inexpensive, easily cleaned and conveniently manipulated by the same hand which supports the spray gun. So also, it will be obvious that my 30 said combination nozzle can readily be used interchangeably with air nozzles having different diameters of their side ports S, according to the nature of the material which is to be sprayed.

However, while I have heretofore described my 35 invention in connection with an embodiment including numerous desirable details of construction and arrangement, many changes might be made without departing either from the spirit of my invention or from the appended claims. For example, since the opposed grooves 4 and G co-operate to afford a single air chamber, it should be obvious without separate illustration that either one of these two cooperating grooves could be omitted; and it likewise should be obvious that 40 the interior groove 20 in the air nozzle may be omitted, since this merely serves to augment the cross-sectional area of the groove g² in the liquid nozzle, into which latter groove the smaller diameter ports 14 open.

The dowel pin 8 may likewise be omitted, since 45 a careful user of such an appliance could determine the proper rotational position of the liquid nozzle (with respect to the gun body) by fitting the inlet end of the port P of that nozzle over the tip of the head H of the movable valve member. If this assembling should not be quite exact, the illustrated difference in diameter between the enlargement S¹ on the said valve member and that of the bore 21 would allow the stem of this 50 member to flex sufficiently to afford a closing of the said port; and particularly so, when the dimensions of the appliance are considerably smaller than they are here illustrated in twice the dimensions of a commercial spray gun.

Moreover, it will be obvious that the novel features of my spray appliance, which I have here 55 illustrated in the form of a spray gun, do not depend on the manner in which this appliance is supported when in use; also, that the here disclosed air control and air equalizing provisions do not depend on the providing of tubular horns for the later emission of the air, since it is immaterial to my invention how the spray-flattening 60 air is discharged after it has been supplied in

equal proportions to the forward peripheral groove in my novel nozzle.

In the claims, the term "passageway" is used 5 for designating the entire series of air passages in the liquid nozzle through which air flows from the air chamber G to the inlets of the side air passages 15; thus, this term includes the inlet port P, the annular groove g between the two flanges 11 and 10, the two ports 14, and the more forward annular groove g².

I claim as my invention:

1. In a spray appliance of the class recited, a body member having a liquid duct and an air duct extending through it; a liquid nozzle having a bore to which the liquid duct leads, the liquid 15 nozzle and the body member being formed for affording an air chamber between them to which the air duct leads; an air nozzle fitted upon the liquid nozzle and provided both with a central air port and two side air ports, the two nozzles 20 being formed to afford an air passageway leading from the said air chamber to the central air port and a second air passageway connecting the air chamber with both of the side air ports; and a valve member movably supported by the body 25 member and directly controlling the inlet of the said second passageway.

2. A spray appliance as per claim 1, in which the said second air passageway has its inlet facing toward the body member, and in which the valve 30 member is movable toward and away from the said inlet.

3. A spray appliance as per claim 1, in which the said second air passageway has its inlet facing toward the body member and its inlet end 35 spaced forwardly from an adjacent frontal portion of the body member, and in which the valve member is movable axially of the said inlet toward and away from the said inlet.

4. A spray appliance as per claim 1, in which 40 the valve member has its forward portion extending continually into a part of the said air chamber and forwardly beyond the body member.

5. A spray appliance as per claim 1, in which 45 the said second air passageway has its inlet facing toward the body and in which the valve member is movable axially of the said inlet toward and away from the said inlet, and means interposed between the liquid nozzle and the body 50 member for fixing the rotational position of the liquid nozzle with respect to the body member so as to maintain the valve member in alinement with the said inlet.

6. In a spray appliance, a body member; a liquid nozzle supported by and in front of the body member; the said nozzle being provided with a liquid passage and with an air passageway which passageway has a rearwardly open inlet spaced forwardly from an adjacent portion of a body 60 member, the body member having passageways for supplying liquid and air respectively to the liquid passage and the air inlet of the air nozzle; a valve member slidably supported by the body member for movement toward and away from the inlet of the said air passageway; spring means continually urging the valve member toward the said air inlet, and means threaded upon the valve member and engaging a portion of the body member for moving the valve member away 65 from the said air inlet against the resistance of the spring means.

7. In a spray appliance of the recited class, a body member, a nozzle disposed forwardly of and clamped against the body member, the said nozzle 70

zle having an air passageway presenting an air inlet facing rearwardly toward the body member; the body member having a forwardly open air supply passage and having a laterally open slot spaced rearwardly from the said passage; the body member also having a longitudinal bore disposed behind the said inlet and forwardly of the said slot, and having a relatively smaller diameter bore extending rearwardly in continuation of the aforesaid bore and opening into the said slot; a valve member including a stem extending successively through and beyond the outer ends of the said two bores, and also including a head adapted to close the said inlet; a wheel threaded on the part of the said stem which is within the said slot, and means associated with the said stem for deterring rotation of the latter; the wheel having its end faces respectively disposed for engaging opposite walls of the said slot, so that rotation of the wheel will move the said stem longitudinally.

8. A spray appliance as per claim 7, including a spring operatively interposed between the said stem and the bottom of the said bore for continually urging the said stem forward so as to press the said wheel against the forward wall of the said slot.

9. In a spray appliance of the class recited, a body member having a liquid duct and an air duct extending through it; a liquid nozzle having a bore to which the liquid duct leads, the liquid nozzle and the body member being formed for affording an air chamber between them to which the air duct leads; an air nozzle fitted upon the liquid nozzle and provided both with a central air port and two side air ports; the air nozzle having an air passage leading from the said air chamber to the central air port and a second air passageway leading from the air chamber to both of the said air ports; the second air passageway having its inlet facing and spaced forwardly from an adjacent portion of the body member, a valve member longitudinally movable upon the body member toward and away from the said inlet for controlling the flow of air through the said second passageway, the body member having a perforated portion through which the valve member slidably extends; a packing member bearing rearwardly against the said perforated portion and gripping a part of the valve member to prevent the latter from rotating about its own axis; a compression spring interposed between the packing member and a more forward portion of the valve member; and a nut threaded upon the valve member behind the said perforated portion and bearing forwardly against the latter perforated portion.

10. In a spray appliance, a liquid nozzle having an axial bore and having three peripheral flanges presenting their peripheries in a common surface of revolution, the liquid nozzle having an air inlet port extending through the most rearward flange and having two auxiliary ports extending through the middle one of the said flanges, the two auxiliary ports being respectively adjacent to diametrically opposite sides of the flange through which they extend and equally spaced from the axis of the first named air port; and a

generally cap-like air nozzle having its bore fitting the peripheries of all three of the said flanges, and having two diametrically opposite air passages the inlet ends of which face the annular space between the two forward flanges of the liquid nozzle.

11. In a spray appliance, a liquid nozzle and an air nozzle as per claim 10, in which the air nozzle has an interior groove facing the said annular space and cooperating with the latter space to afford an annular air chamber interposed between the outlets of the two auxiliary ports of the liquid nozzle and the inlet ends of the said diametrically opposite air ports.

12. As a constituent for the head portion of a spray appliance of the class described, a nozzle having two peripheral flanges spaced longitudinally of the nozzle by a groove; the rearward flange having an air inlet port extending through it and the forward flange having two relatively smaller diameter air ports extending through it, the said smaller ports being respectively adjacent to opposite sides of the nozzle and having their axes in a common plane diametric of the nozzle, the said plane being at right angles to a plane diametric of the nozzle and in which latter plane the axis of the first named air port lies.

13. In a spray appliance of the class in which a liquid nozzle is disposed forwardly of a body member, and in which an air nozzle is fitted over the liquid nozzle and is provided with two diametrically opposite air discharge passages, a liquid nozzle having two longitudinally spaced peripheral flanges both disposed rearward of the inlets of the said air discharge passages, the more rearward flange having a single air inlet port extending through it and the other flange having two relatively smaller ports extending through it, the said smaller ports having their axes in a plane diametric of the nozzle and at right angles to the plane diametric of the nozzle in which the axis of the inlet port is disposed; the liquid nozzle having an annular air supply groove from which the inlet port leads, and having a peripheral groove into which both of the smaller diameter ports open and from which the air discharge passages lead.

14. In a spray appliance, a body member provided with a liquid passage and an air supply passage; a liquid nozzle abutting rearwardly against the body member and having a bore into which the said liquid passage opens; and an air nozzle clamped rearwardly against the liquid nozzle and formed for affording two air discharge passages presenting forwardly converging outlet portions; the body member and the liquid nozzle having their abutting portions formed to afford an annular air chamber between them, to which chamber the air supply passage leads; the liquid nozzle having an air-passageway presenting a rearwardly open inlet to the said air chamber and leading to both of the said air discharge outlet portions; and a valve member supported solely by, and projecting forwardly beyond the body member; the valve member being movable toward and away from the said inlet of the air-passageway for controlling the said inlet.

FRITZ WAHLIN.
